US00D843350S

(12) **United States Design Patent** (10) **Patent No.:** **US D843,350 S**
(45) **Date of Patent:** **** Mar. 19, 2019**

(54) **WIRELESS AUDIO HEADSET**

(71) Applicant: **Hand Held Products, Inc.**, Fort Mill, SC (US)

(72) Inventors: **Robert Vargo**, North Huntingdon, PA (US); **Richard Sharbaugh**, New Kensington, PA (US); **Andrew Lyle Walston**, Clinton, WA (US); **Graham Byrne**, Wexford, PA (US); **Bryan DiPiazza**, Belle Vernon, PA (US); **Leslie McKay**, Jeannette, PA (US); **Matthew W. Shope**, Beaver Falls, PA (US)

(73) Assignee: **HAND HELD PRODUCTS, INC.**, Fort Mill, SC (US)

(**) Term: **15 Years**

(21) Appl. No.: **29/608,666**

(22) Filed: **Jun. 23, 2017**

Related U.S. Application Data

(63) Continuation of application No. 29/530,600, filed on Jun. 18, 2015, now Pat. No. Des. 790,505.

(57) **CLAIM**

The ornamental design for a wireless audio headset, as shown and described.

DESCRIPTION

FIG. 1 is a front perspective view of a wireless audio headset in accordance with the present design; FIG. 2 is a front elevation view thereof; FIG. 3 is a back elevation view thereof; FIG. 4 is a left elevation view thereof; FIG. 5 is a right elevation view thereof; FIG. 6 is a top plan view thereof; and, FIG. 7 is a bottom plan view thereof.

Broken lines in the form of an alternating series of relatively short dashes and relatively long dashes represent bounds of the claimed design, and the broken lines immediately adjacent the shaded areas represent the bounds of the claimed design, while all other broken lines are directed to environment and are for illustrative purposes only; the broken lines form no part of the claimed design.

1 Claim, 7 Drawing Sheets
